UNITED STATES PATENT OFFICE.

WILLIAM DOUCETTE, OF REVERE, AND HOWARD L. SULIS, OF BOSTON, MASSACHUSETTS,
ASSIGNORS TO THE SAID SULIS, HOWARD G. TRECO, JOHN A. O'CONNOR, AND ELI
SIEGEL, DOING BUSINESS UNDER THE FIRM-NAME OF COMBINATION DRINKING
FOUNTAIN COMPANY, OF BOSTON, MASSACHUSETTS.

DRINKING-FOUNTAIN ATTACHMENT FOR FAUCETS.

1,175,137.

Specification of Letters Patent. Patented Mar. 14, 1916.

Application filed August 7, 1915. Serial No. 44,298.

To all whom it may concern:

Be it known that we, WILLIAM DOUCETTE and HOWARD L. SULIS, citizens of the United States, residing, respectively, at Revere, in the county of Suffolk and State of Massachusetts, and Boston, in the county of Suffolk and State of Massachusetts, have invented a new and useful Drinking-Fountain Attachment for Faucets, of which the following is a specification.

The object of our invention is to provide a drinking fountain coupling for ordinary faucets, which may readily be associated with the end of the nozzle of the faucet and secured thereto, and adapted to normally permit the discharged water from the faucet to pass directly through the main conduit of said coupling and otherwise to direct the water through the fountain member of said coupling; said fountain member being provided at its lower end with a drip-lug for running the overflow water from the cup of the same back into the bowl, and at the delivery end thereof with a non-adjustable pressure-controlling-collar which cuts down the force of the water passing therethrough and delivers the same through the cup of said fountain member in proper condition for drinking purposes.

To these as well as other ends, our invention consists in the novel features of construction, combination and arrangement of parts set forth and described in the following specification.

Referring to the accompanying two sheets of drawings—Figure 1, is an elevation showing our device attached to an ordinary sink faucet, with the fountain-arm supporting the drinking cup in the “drinking position”, the dotted lines indicating the “non-drinking position” of the drinking cup, in which position the faucet discharges through the main nozzle of the device. Fig. 2, is a part sectional view taken on line 2—2 in Fig. 1, looking in the direction of the arrows. Fig. 3, is the same view as Fig. 1, but shows the fountain-arm shifted with the cup in the non-drinking position, in which position the directing valve of the device is ported to “full open” for permitting the discharge, from the faucet, to flow through the main nozzle of the device. Fig. 4, is the same

view as Fig. 2, but shows the drinking cup shifted to the non-drinking position, corresponding to Fig. 3, which positions the valve to discharge the water from the faucet through the main nozzle of the device. Fig. 5, is a front view of the device, showing the drinking cup in the non-drinking position, corresponding to Figs. 3 and 4. Fig. 6, is a view showing our device coupled with the nozzle of an ordinary bath-room faucet, which is not provided with a threaded coupling end of the type shown in Figs. 2 and 4; thus requiring a special type of coupling means for securing the device to the faucet. Fig. 7, is a part section taken on line 7—7 in Fig. 6, looking in the direction of the arrows, showing the split-coupling collar which secures the device to the plain nozzle of the faucet. Fig. 8, is a section taken on line 8—8 in Fig. 7, looking in the direction of the arrows, showing a plan of the split-coupling collar with the union sleeve removed therefrom. Fig. 9, is a plan view of the union sleeve showing the flange of the same cut out to permit the same to be fitted over the ears of the split-coupling collar, shown in Fig. 8. Fig. 10, is a sectional view taken on line 10—10 in Fig. 7 looking in the direction of the arrows, showing the directing-valve ported to deliver the water from the faucet through the drinking cup, which shows the true position of the valve corresponding to Figs. 1 and 6 in which the fountain-arm, supporting the drinking cup, is set in the drinking position. Fig. 11, is a section taken through line 11—11 in Fig. 2 looking in the direction of the arrows, showing the pressure-controlling-collar and the sanitary and filtering fountain cup of the device. Fig. 12, is a plan view of the pressure-controlling-collar shown in Fig. 11.

Like numerals refer to like parts throughout the several views of the drawings.

The numeral 1 is a water supply pipe provided with the faucet 2 which is operated and controlled through the manipulation of the faucet-handle 3.

4 is the delivering nozzle of the faucet which is usually found provided (especially in the case of sink as well as other faucets) with the threaded end 5 for the purpose of coupling a hose or other pipe connection

with the faucet for allowing the water, flowing from the opening 6 of the faucet, to enter the same.

7 is the valve body member of the device, and is provided with the coupling projection 8 which has the receiving-port 9 and the main delivering nozzle 10 which has the discharge opening 11. The coupling-projection 8, when used with a faucet provided 10 with the threaded end 5 shown in Figs. 1, 2, 3, and 4, is provided with the nipple 12 which has the flange 13 projecting beyond the coupling-projection 8, which nipple may be screwed into the coupling-projection 8, as shown in Fig. 2, or otherwise rigidly secured thereto, as shown in Fig. 4, as by being sweated or driven into place.

Associated with the flange 13 of the nipple 12 is the coupling-sleeve 14 which is internally threaded to engage with the threaded end 5 of the faucet, for coupling the device into working position therewith. The washer 15 is preferably inserted between the flange 13 and the bottom of the 25 faucet for making a tight joint between the two, when the same are coupled together,—it being understood that the coupling-sleeve 14 is free to turn on the device for the purpose of coupling the same with the faucet. 30 The valve body member 7 of the device is provided with the tapered hole 16, the drinking cup-end 17, preferably having the larger opening of said tapered hole, and the cut-out 18 which forms the stop for the two positions of the directing-valve 19. The tapered directing-valve 19 fits and operates within the tapered hole 16 of the valve-casing member 7, and is provided with a main discharge port 20 and a by-pass or fountain port 21,—40 the main discharge port 20 being open clear through the valve 19 (Figs. 4 and 10), while the by-pass or fountain port 21 opens into the chamber 22 of the hollow fountain-arm 23 (Figs. 2 and 7) which arm may be made integral with said directing-valve 19, or otherwise rigidly secured thereto.

Secured within the chamber 22 of the fountain-arm 23 is the pressure-controlling collar 24 which has the passage 25 provided 50 with the flared or tapering opening 26 across which is positioned the stream-dividing-pin 27 which lies directly over the passage 25, as shown in Figs. 11 and 12. The projecting end 28 of the fountain-arm 23 carries secured thereto the sanitary fountain bubbling or drinking cup 29, which may be provided when desired with the lower gauze-strainer member 30 and the upper gauze-strainer member 31, between which is 55 the supply of filtering material 32 shown in Fig. 11.

The cup 29 is provided with the delivering-plate 33 which has the outlet 34 through which the drinking water, coming from the 60 faucet, is discharged, which water passes

through the fountain-arm when the same is shifted to the drinking position of the device, as shown in Figs. 1, 2 and 6. The fountain end of the valve 19 is provided with the limiting-pin 35 which operates in the cut-out or recess 18 of the valve member 7 provided for the purpose, affording thereby a stop for the fountain-arm in both the drinking and the non-drinking positions, as shown in Figs. 1 and 3, respectively. The lower end of the fountain-arm 23 is provided with the drip-lug 36 for guiding the water, overflowing from the drinking cup, which flows along the underside of the fountain-arm 23, into the basin in which the faucet discharges, thus preventing a stream from shooting off of the fountain-arm when the drinking fountain is in operation,—the water flowing along said fountain-arm (when in the inclined position shown in Fig. 1) having the tendency to continue along the same angle when leaving the fountain-arm, and thus throws a stream of water while the fountain is discharging.

Where the device is to be secured to a faucet which is not provided with a threaded coupling end 5, shown in Figs. 2 and 4, the coupling-projection 8 is preferably provided with the threaded flange 37 (Figs. 7 and 10) which engages with the coupling-sleeve 38, which coupling-sleeve is in turn provided with the flange 39 having the cut-out 40 for permitting said coupling-sleeve to pass over the clamping-ears 41 of the split-coupling-collar 42 which is provided with the supporting-flange 43 upon which the flange 39 of the coupling-sleeve 38 rests. The split-coupling-collar 42 is clamped into position with the nozzle 4 of the faucet, by means of the clamping-screw or stud 44, clamping the ears 41, provided at the split 45, together,—it being understood that the coupling-sleeve 38, when the flange 39 rests on the flange 43 of the split-coupling-collar, is free to turn on the same, in which event clearance must be provided between the flange 43 and the underside of the ears 41, for the purpose, as shown in Fig. 7.

The take-up end of the directing-valve 19 is provided with the tongue 46 over which is fitted the retaining-collar 47 which is provided with a slot for fitting over said tongue. The retaining end of the directing-valve 19 is also provided with the tapped hole 48 into which is screwed the retaining-stud 49 by means of which stud the directing-valve 19 may be regulated to operate freely within the valve member 7 without leakage,—it being understood that a clearance is provided between the end of the directing-valve and the retaining-collar and stud, as shown in Figs. 2 and 4, for take-up purposes.

Having thus described the parts of our 130

invention in detail, the manner in which the same is applied to the faucet and operated therewith, is as follows. Where the attachment is to be coupled with a faucet, provided with the coupling end 5 (shown in Figs. 1, 2, 3, and 4) a washer of leather or other suitable material is inserted within the coupling-sleeve 14, and the same is then screwed on to the threaded end 5 of the nozzle 4 of the faucet, for coupling the attachment with the same, as shown in the last mentioned figures,—it being observed that the ports in the directing-valve are set ninety degrees apart on centers in the drawings, therefore requiring a swing of ninety degrees for the fountain-arm which operates the valve for positioning the same from one position to the other (Fig. 1). With the fountain-arm and cup shifted to the position shown in Fig. 3, which is the "non-drinking" position, the main port 20 of the directing-valve 19 is "full open" to the faucet port for allowing the discharge of water from the same, when the faucet handle 3 is turned on, through the device without interference, thus permitting the faucet to serve in its usual capacity as though the attachment was not there at all.

When it is desired to use the drinking cup for drinking purposes, the fountain-arm 23 is shifted to the opposite position, shown in Figs. 1, 2 and 6, in which position the by-pass port 21 is ported to receive the discharge of water from the faucet, when the same is turned on. The water entering the by-pass port 21 flows up through the chamber 22 of the fountain-arm 23 and passes through the hole 25 of the pressure-controlling-collar 24 supplied in the chamber 22. As the water flows through the passage 25, it strikes the dividing-pin 27 which divides the stream and sprays the water to each side of the chamber 22, and thus greatly cuts down the pressure of the same, so that the pressure of the water is decidedly decreased and permits only of a slight bubbling through the outlet 34 of the delivering cup 33, as shown in Fig. 11. By varying the size of the passage 25 and the diameter of the dividing-pin 27 the pressure of the water, flowing through the fountain-arm 23, may be regulated according as desired, for permitting the pressure of the water, flowing through the cup, to be properly conditioned for drinking purposes.

Where the attachment is to be secured to a faucet which is not provided with the coupling end 5, as the one shown in Fig. 6, a split-coupling-collar-union of the type shown in Figs. 6 and 7 may be used to advantage,—the split-coupling-collar, permitting the securing of the same to the faucet for forming the support for the device and couples the same with the faucet, offering every advantage to it that has tofore

been described in connection with the other type of faucet.

The stop-pin 35, working in the cut-out 18, is allowed to come up against the sides of said cut-out in either position of the fountain-arm, as shown in Figs. 1 and 3.

It may be noted here that it is not absolutely necessary for the ports of the directing-valve to be centered 90 degrees apart, as heretofore mentioned,—it being understood that any angle will suffice, providing the two ports are independent of one another and do not interfere with each other, for by increasing the diameter of the directing-valve the ports may be centered at an angle less than 90 degrees apart.

It may also be understood, that the by-pass port need not necessarily be as large as that of the main port, which port should have an area equal to the discharge opening of the faucet for permitting any discharge that the faucet ejects to pass through it conveniently.

It may be observed that the device offers a very simple and practical faucet accessory, which may be coupled with any type of faucet, and is adapted to permit the same to discharge its water through it without interference, and at the same time, when desired, may be put into action as a sanitary drinking fountain for drinking purposes; thus the attachment may be alternatively employed to either permit the discharge of the faucet directly through it or to serve as a drinking fountain, the same being exceptionally useful in the household, shops and factories. Also, the attachment introduces a sanitary feature for drinking purposes and greatly reduces the amount of waste water usually resulting from the use of the ordinary faucet for drinking purposes where the same is not of the fountain type.

While the preferred embodiments of the invention have been described in detail, it will be understood that we do not wish to be limited to the particular construction set forth, since various changes in the form, material, proportion and arrangement of parts, and in the details of construction may be resorted to without departing from the spirit and scope of the invention, or destroying any of the advantages contained in the same heretofore described and defined in the subjoined claims.

What we claim is—

1. A sanitary drinking fountain attachment for faucets comprising a valve casing member having an inlet and an outlet and provided with coupling means for securing the inlet of the same with the discharge nozzle of the faucet, for forming an extension thereof; a directing-valve, provided with a discharge-port and a fountain-port, and adapted to operate within said valve casing member for registering either of said ports

with said inlet at will; a hollow fountain-arm secured to and extended beyond said directing-valve and adapted to operate therewith and provided with a drip-lug at the lower end thereof, and positioned in a plane at right angles with the axis of said directing-valve, the hollow of said arm being open to said fountain-port; a pressure-reducing collar fitted within the hollow of said fountain-arm provided with a flared aperture communicating with the hollow of said arm and having a cross-bar intersecting said aperture; a sanitary drinking cup secured to the free end of said fountain-arm for delivering the water flowing through the same; and means for holding said directing-valve in working relation with said valve casing member.

2. A drinking fountain coupling for faucets, comprising a casing member adapted to be coupled with the end of the nozzle of a faucet for receiving the discharge therefrom and provided with an auxiliary discharge

for said faucet; a horizontal and angularly operated plug-valve, provided with a through-port for normally discharging the water from the faucet therethrough and a fountain-port independent of said through-port, and having a tubular arm open to said fountain-port positioned within a plane at right angles with the axis of said plug-valve and provided with a drip-lug at the bottom thereof, also positioned within said plane; a pressure-controlling-collar, inserted within said tubular arm, having an aperture communicating with the chamber of said tubular arm and provided with a stationary bridge member crossing the mouth of said aperture; and a cup member secured to the free end of said tubular arm and forming an outlet therefor, substantially as shown.
